UNITED STATES PATENT OFFICE.

GEORGE HENRY WHEARY, OF RACINE, WISCONSIN.

LID OR COVER SECTION FOR WARDROBE TRUNKS.

Application filed January 27, 1923. Serial No. 615,218.

My invention relates to improvements in lid or cover sections for wardrobe trunks.

The object of my invention is to provide an inexpensive lid section of improved appearance and increased strength.

More particularly stated, it is my object to provide a shallow lid section which may be closed down upon the clothing suspended within the wardrobe section of the trunk, and which will be utilized to hold the hangers in position by pressure upon such clothing as may be supported by said hangers, the valance of the lid section constituting also a reenforcing corner iron which extends continuously around three sides of the lid section and laps over upon the top thereof in such a manner as to form a connecting member for the top, front, and end pieces.

In the drawings:

Figure 1 is a plan view of a wardrobe trunk lid section embodying my invention.

Figures 2, 3, and 4 are front, end, and rear elevations respectively.

Figure 5 is a sectional view drawn on line 5—5 of Figure 1.

Figure 6 is a sectional view drawn on line 6—6 of Figure 1.

Figure 7 is an interior isometric view of a fragment of the lid section.

Figure 8 is a plan view of the reenforcing corner piece.

Figure 9 is a sectional view of the same drawn on line 9—9 of Figure 8.

Figure 10 is a view showing a fragment of the blank or metal strip from which the valance is formed.

Like parts are identified by the same reference characters throughout the several views.

The lid section shown in the drawings is of the general type disclosed in my former Patent No. 1,184,175, dated April 6, 1915, for an automatic locking means for trunks, but the improved lid section herein shown comprises a main plate composed of a wooden member 1 interposed between fiber sheets 2 and 3. The end and front margins are provided with depending flanges 4—4 and 5 respectively, these flanges being formed of wooden strips placed edgewise on the main plate and secured thereto by glue or nails and additionally connected therewith by the valance strip as hereinafter explained.

A sheet 6 of fabric is applied to the inner surface of the main plate with interposed padding 7 throughout the central portion.

The fabric extends outwardly from the padding and is preferably glued to the plate, the margins of the fabric being wrapped about the flanges 4 and 5 and preferably glued thereto. The ends of the flanges 4 are connected to the flange 5 by metallic corner pieces 8 having hook-shaped portions 9 adapted to engage the exposed margins of the wooden flanges 4—4 and 5, and also having a foot piece 10 suitably apertured whereby it may be connected with the main plate by one or more screws. These screws also serve to draw the corner piece toward the main plate and force the hooks 9 into rigid engagement with the margins of the flanges 4 and 5, the hook margins being preferably forced into the wood to some extent. A strip of metal is then applied to the outer surfaces of the main plate and its flanges 4 and 5. This metal strip initially comprises a flat blank having notches 12 along one margin. The marginal portions 13 of this blank are bent inwardly in the form of a rounded elbow along the longitudinal dotted line appearing in Figure 10. The strip is also bent at right angles thereto from the central portion of the notch 12 to the opposite margin, i. e., along the transverse dotted line indicated in Figure 10, thereby forming end portions 14 and a central portion 15 adapted when assembled to form a metallic covering for the ends and front of the main plate and its flanges, with the marginal portions 13 lapping upon the upper surface of the main plate along its ends and front margins. The portions 13 are secured to the main plate by a row of nails or rivets 18, and the portions 14 and 15 are similarly secured to the flanges 4 and 5 by nails or rivets 17. The portions 14 and 15 are wider than the flanges 4 and 5 and project downwardly therefrom to form a valance 19.

The notches 12 are located at the corners and permit infolding the marginal portions 13 upon the main plate as above described. These corners are then covered by corner plates 20 which may, for the purposes of this description, be assumed to be corner plates of ordinary type. They are provided with elbow shaped doweling members 21 adapted to co-operate with correspondingly formed doweling sockets on the wardrobe section of the trunk.

The metallic reenforcing strip, including the portions 13, 14, and 15, may be termed the valance strip, although the function of

this strip is not only to provide a valance for the cover or lid section of the trunk, but to also constitute a protecting reenforcement for the margin of the main plate and its flanges, and a connecting member for securing the flanges 4 and 5 to the main plate. The rivets 17 and 18 extend at right angles to each other, and as these rivets form continuous rows along the ends and front margin of the cover, it will be obvious that the valance strip is rigidly secured in position and that it is adapted to hold the flanges 4 and 5 to the cover plate regardless of the co-operating securing means above described such for example as glue interposed between the flanges and the cover plate and the corner pieces 8. These corner pieces, however, are adapted to cover meeting edges of the fabric sheet 6 where the fabric sheet is cut away or gored to allow it to be adjusted to the flanges 4 and 5, and said corner pieces also form an attractive feature of the cover section, being preferably nickel plated. They, therefore, not only perform the mechanical function of reinforcing the corners, but they add to the appearance of the cover section and serve as covering members for the margins of the fabric.

I claim:

- 30 1. A cover or lid section for wardrobe trunks comprising the combination of a main plate, marginal end and front flanges therefor, a reenforcing valance strip secured to said flanges with its lower margins projecting below the flanges and its upper margins lapped upon the main plate and secured

thereto, co-operating interior corner pieces having hook-shaped portions engaging the flanges, and a foot piece in drawing engagement with the main plate, whereby the hook portions may be drawn into embedded relation with the flanges.

2. A cover or lid section for wardrobe trunks comprising the combination of a main plate having its interior surface centrally padded and provided with depending marginal flanges; a fabric covering for the padding, the marginal portions of the plate, and the flanges; reenforcing interior corner pieces having hook-shaped portions to engage the meeting end portions of the flanges at the corners, and also having drawing engagement with the main plate; and an exterior metallic valance covering the outer surfaces of the flanges and extending upon and secured to the upper surface of the main plate.

3. In a cover or lid section for wardrobe trunks, a metallic valance extending continuously along the ends and front of the section and having an inturned upper marginal portion notched at the corners and secured to the upper surface of said section, means for also securing the valance to the sides of said section, and corner pieces covering the corners and notched portions of the valance strip, said corner pieces having elbowed doweling members adapted to receive counter-part doweling members on the wardrobe section of the trunk.

GEORGE HENRY WHEARY.
